CLARENCE B. FOSTER, OF GLENDALE, CALIFORNIA, ASSIGNOR OF ONE-SIXTH TO FREDERICK L. FEISTHAMEL, ONE-SIXTH TO ARTHUR J. CARR, AND ONE-SIXTH TO THOMAS A. COLLINS, ALL OF LOS ANGELES, CALIFORNIA.

FABRICATED-STEEL DERRICK OR TOWER CONSTRUCTION.

Application filed July 17, 1926. Serial No. 123,135.

This invention relates to an improved type of fabricated steel derrick or tower construction, and is particularly directed to that class of structure in which the corner leg columns and associated girts are formed of standard structural angles.

More specifically, the present invention is directed to certain improvements in the construction of the type of derrick or tower disclosed in my copending application, Serial No. 123,134, and has for an object to provide a structure including a triple-angle type of corner leg column in which the three angle leg sections thereof are arranged in back-to-back relationship to form a leg column cross-shaped in cross section, and with the leg angles secured together in intimate contacting relationship throughout their lengths.

Another object is to provide an improved form of compound gusset bracket associated with the corner leg column and the girts and braces of the adjacent sides of the structure to form reinforcing means free from connection to the outer intermediate leg angle, said bracket constituting a means providing direct connection between the girts and braces of the adjacent sides.

A further object is to provide a compound horizontal and vertical gusset bracket which may be formed of a single sheet metal stamping bent to form a horizontal gusset of double thickness, and two vertical gussets angularly disposed to each other.

Various other objects and advantages will be more fully apparent from the following description of the accompanying drawings which form a part of this disclosure, and which illustrate a preferred form of embodiment of the invention.

Of the drawings:

Fig. 1 is an elevation of a tower structure constructed in accordance with the present invention.

Fig. 2 is an enlarged plan section, partly broken, taken on line 2—2 of Fig. 1.

Fig. 3 is a fragmentary vertical section taken on line 3—3 of Fig. 2.

Fig. 4 is a fragmentary elevation of a corner portion of the tower, looking outwardly in the direction indicated by the arrow 4 in Fig. 2.

Fig. 5 is a plan view of the gusset bracket blank before being bent to form.

Fig. 6 is a perspective view of one of the gusset brackets as it will appear before the bolt holes are punched therein.

Fig. 7 is an elevation of a drilling derrick constructed in accordance with the present invention.

Fig. 8 is an enlarged fragmentary elevation of one corner of the derrick as it will appear with the outer intermediate leg angles removed.

Fig. 9 is a similar elevation showing the angle joint-plates which may be used to replace the removed intermediate leg angles.

In the construction disclosed in my other application, above identified, the corner leg column consisted of two opposed inner leg angles and an outer intermediate leg angle spaced from said inner leg angles to accommodate the anchor plates of the respective compound gusset brackets and each of said brackets provided a horizontal gusset of single thickness.

For certain purposes it has been found desirable to provide a triple angle leg column in which the several angle leg sections are clamped together in intimate contacting relationship throughout their respective lengths so as to produce a more rigid corner column in which shear strains on the bolts or rivets of the leg angles is minimized by the resistance against relative slippage of the respective leg angles due to the intimate clamped contact of the leg angles, it being recognized that such bolts or rivets cannot be subjected to shear until slippage occurs and that the resistance to slippage of clamped surfaces has an accepted value of approximately 18,000 pounds per square inch, which will substantially equal the shear strength of the bolts or rivets used. It will thus be quite evident that the importance of closely contacting and tightly clamping together the leg angles comprising the corner legs assumes a major aspect of this invention.

The form of gusset bracket incorporated in the structure herein disclosed is of particular value by reason of the horizontal gussets of double thickness thereby provided and for the reason that the vertical gussets are joined to each other throughout their height, a further advantage being that the bracket is fully independent of any connection with the outer intermediate leg angle.

which is intended for removal for the conversion of the structure from a heavy duty type to one adaptable for lighter service.

In Figs. 1 to 6 there is illustrated a heavy duty type of structure in the form of a square tower having four corner leg columns connected together by transverse girts and diagonal sway braces which form the respective sides of the structure. The several corner leg columns are of duplicate construction and each is formed of three strings of angle sections disposed in back-to-back relationship to form a leg column substantially cross-shape in cross section, with the sections of each string vertically aligned to abut one upon the other.

The inner opposed angle leg sections 10 and 11 are disposed with their respective flanges 10^a and 11^a extended in the planes of the respective adjacent sides of the tower and with their other flanges 10^b and 11^b extending outwardly, and the respective leg sections 10 and 11 of the several corner leg columns are arranged in horizontal alignment so as to bring the several lines 12 of abutment at coincident vertically spaced intervals, whereby the tower may be assembled progressively in stories or tiers to a horizontal level. The outer intermediate angle leg sections 13 are disposed between the inner opposed leg sections 10 and 11 with their flanges in direct intimate contact with the flanges 10^b and 11^b of said inner leg angles and said outer leg angles are disposed in break-joint relationship with the inner leg angles 10 and 11 so that their lines 14 of abutment come half way between those of the inner leg angles, as shown in Fig. 1.

Disposed at each end of each pair of inner leg angles sections 10 and 11 is a compound gusset bracket of novel construction, formed to provide two vertical gusset plates 15 and 16 disposed at right angles to each other and joined at their inner vertical edges, and two horizontal gusset plates 17 and 17^a extended from the respective vertical gusset plates 15 and 16 and disposed in overlapping relationship to constitute a horizontal gusset of double thickness. This gusset bracket is preferably formed of a single sheet metal stamping of the contour illustrated in Fig. 5, said stamping being formed with a central aperture 20 and a slit 21 extending inwardly to intersect said aperture. In the forming of the bracket from said stamping, the vertical gusset portions 15 and 16 may be bent towards each other, along the line 18, the portion 17 being then bent at right angles to the portion 15, along the line 15^a, and the portion 17^a being subsequently bent, along the lines 16^a, to position parallel and in overlapping relationship with the portion 17, thus forming a bracket of substantially the shape illustrated in Fig. 6, said bracket being, by preference,

subsequently punched or bored to accommodate the several rivets or bolts by which it is secured into the tower structure.

At each level or tier of the tower structure, as defined by the line 12 of abutment between the vertically adjacent inner leg angles, two of the above described gusset brackets are positioned in reverse relationship with their respective horizontal gusset plates 17^a back-to-back and their respective vertical gusset plates extended in opposite directions; and such brackets are disposed so that their vertical gusset plates 15 and 16 closely engage the inner surfaces of the flanges 10^a and 11^a of the respective inner leg angles 10 and 11, as clearly shown in Fig. 2, these particular gusset brackets being indicated generally, by the reference characters A and B.

Certain other intermediate gusset brackets C and D, similar to those above described, are preferably located at approximately the middle of the respective pairs of inner leg angles 10 and 11 of each corner column and are disposed in the same relationship to the several leg angles as are the gusset brackets A and B, that is, each pair of gusset brackets C and D are in reverse relationship vertically with their vertical gusset plates engaging the leg angles 10 and 11 and their horizontal gussets in back-to-back relationship.

In erecting the structure, the several leg sections are clamped together in contacting relationship, by bolts 22, 23, and 24, the bolts 22 extending through the flange 10^b of the respective leg angles 10 and the contacting flange of the outer leg angle 13, opposite the brackets A and B, the bolts 23 extending through said flange 10^b and said outer leg angle 13, adjacent the brackets C and D, and the bolts 24 extending through said flanges, between the pairs of gusset brackets; and by bolts 26, 27, and 28 extending in like manner through the flange 11^b of the respective inner leg angles 11 and the contacting flanges of the respective outer leg angles 13, it being understood that a greater number of the bolts 24 and 28, between the pairs of gusset brackets, may be provided if desired.

The side structure connecting the adjacent corner leg columns is illustrated as comprising a plurality of girts and braces, and as such girts and braces included in each story or tier are duplicates of those included in the other stories or tiers, only one set thereof will herein be described in detail. The sides of each story includes lower and upper transverse marginal girts 30 and 31, so called because they define the respective lower and upper margins of the respective story, a pair of intermediate transverse girts 32 and 33, a lower pair of diagonal sway or anti-vibration braces 34 and 35, and an upper pair of similar sway or anti-vibration braces 36 and 37.

The several transverse girts are of angle form and may be of identical size and shape, with the ends of their horizontal flanges cut angular as shown in Fig. 2, and the respective ends of each girt are disposed in nested relationship inside the cooperating gusset bracket with the horizontal flange of said girt engaging the horizontal gusset plate 17 thereof and the vertical flange of said girt 10 engaging the adjacent vertical gusset plate of said bracket. This relationship, will in the completed structure, dispose the several girts in pairs, which pairs are secured together at spaced intervals by bolts 38 extending through the horizontal flanges of the respective girts and through suitable intermediate spacers 39.

Each end of each girt is secured to the associated gusset bracket by a bolt 40, extending through its vertical flange and the adjacent vertical gusset plate portion of said bracket, and is secured to said bracket and the adjacent inner leg angle by a bolt 41 extending through said vertical gusset portion 25 of the bracket and through said inner leg angle, said vertical gusset plate portion of the bracket being thus clamped between said girt and said inner leg angle, as is plainly evident in Fig. 2. Bolts 42 extending through the horizontal flanges of the respective girts and through the horizontal gusset plates 17 and 17^a of each pair of brackets A, B, and C, D, thus securing said pairs of brackets together independently of 35 their connection with the corner legs, and said horizontal gusset plates 17 and 17^a are further secured together independently also of the girts, by bolts 43.

The several diagonal sway braces are of 40 angle form and their ends are swayed to bring both flanges thereof to vertical parallel contact thus providing securing ends of double thickness. These respective sway braces are each secured to the vertical gusset plate portions of the associated brackets by bolts 44 and 45, the bolts 44 extending through said braces and the vertical gusset plate portions of said brackets and the bolts 45 extending through said braces, said brackets and the adjacent inner angle leg sections.

The above described construction provides a tower or similar structure in which the respective corner leg columns each consists of three strings of angle leg sections arranged in back-to-back relationship and secured together throughout their lengths in intimate contact to form corner legs substantially cross-shape in cross section, and 55 transverse girts and braces connected to said corner legs by compound horizontal and vertical gusset brackets, with such gusset brackets forming reinforcing connections joining the horizontal girts and braces 60 of one side of the tower to those of the

adjacent sides thereof. Such construction further provides corner leg columns consisting of two vertical strings of opposed inner corner leg angles and an intermediate string of outer corner leg angles connected together in a manner permitting a removal of 70 said outer leg angles to convert the structure to one adaptable for use for lighter service.

In Fig. 7, the above described construction is shown incorporated in an oil well drilling derrick, and when such a derrick is to be converted to a lighter pumping derrick the outer leg angles 13 thereof will be removed, Fig. 8 showing a corner of the derrick with such leg angles removed. In 80 certain instances the structure may be used in this condition, but it is believed to be desirable to substitute for the removed leg angles, short angle joint-plates 50, as shown in Fig. 9, these joint-plates being secured 85 in place by bolts 51 which extend through the same bolt holes as did the respective bolts 22, 23, 26, and 27 previously used to secure the leg angles 13 in place.

The several stories or tiers of the tower 90 are herein described as being of like construction, but it is to be understood that this has more particularly reference to the major portion thereof, for it will be evident, particularly to those skilled in the oil 95 industry that in a well derrick certain portions of the structure will necessarily be somewhat modified to accommodate the walking-beam draw-works, and other portions of the drilling or pumping equipment 100 and also that suitable provisions will be made for the derrick ladder, platform, water-table, crown-block, etc.

While the structure herein illustrated and described is fully capable of fulfilling all of 105 the objects primarily stated, it is to be understood that I do not wish to restrict the present invention to the specific embodiment herein disclosed, for it is susceptible of embodiment in various other forms, all coming 110 within the scope of the claims, which follow.

I claim as my invention:

1. In a structure of the nature disclosed, the combination of: relatively spaced triple-angle corner leg columns, each comprised of 115 only two opposed inner leg angles and one intermediate outer leg angle disposed in intimate back-to-back contact to form a compact corner leg column substantially cross-shape in cross section; transverse girts forming 120 the respective sides of the structure and connecting the adjacent corner leg columns, the girts of each side being secured at opposite ends to the adjacent inner leg angles of the associated leg columns; means connecting the inner leg angles of each corner column independently of the intermediate leg angles thereof; and independent removable means for securing the intermediate leg angle of each corner column to the inner 125

leg angles thereof, whereby the intermediate leg angles may be independently removed.

2. In a structure of the nature disclosed the combination of: relatively spaced triple-angle corner leg columns, each comprised of only two opposed inner leg angles and one intermediate outer leg angle disposed in intimate back-to-back contact to form a compact corner leg column substantially cross-
10 shape in cross section, with one flange of each inner leg angle disposed parallel to the adjacent side of the structure; transverse girts forming the respective sides of the structure and connecting the adjacent corner leg columns, the girts of each side being secured to the respective parallel flanges of the adjacent inner leg angles; means connecting said flanges of both inner leg angles of each corner leg column independently of the intermediate leg angle thereof; and removable means for securing the other flanges of both inner leg angles of each corner leg column to the intermediate leg angle thereof, whereby said intermediate leg angle may be independently removed.

3. In a structure of the nature disclosed, the combination of: relatively spaced triple-angle corner leg columns, each comprised of only two opposed inner leg angles and one intermediate outer leg angle disposed in intimate back-to-back contact to form a compact corner leg column substantially cross-shape in cross section; transverse girts forming the respective sides of the structure and connecting the adjacent corner leg columns; means for securing the girts of each side to the adjacent inner leg angle of each associated corner column; and independent removable means for securing the intermediate leg angle only to the inner leg angles, whereby said intermediate leg angle may be separately removed.

4. In a structure of the nature disclosed, the combination of: relatively spaced triple-angle corner leg columns, each comprised of only two opposed strings of inner leg angles and one intermediate string of outer leg angles arranged in intimate back-to-back contact to form a compact corner leg column substantially cross-shape in cross section, the leg angles of each string being vertically aligned to abut one upon another, the inner leg angles of said two opposed strings being horizontally aligned so that the leg angles of both said opposed strings abut at coincident levels, and the intermediate leg angles being disposed to break-joint with the inner leg angle; transverse girts forming the respective sides of the structure and connecting the adjacent corner leg columns; means for securing the girts of each side to the adjacent inner leg angles of each associated corner column; and independent removable means for securing the intermediate leg angle only to the inner leg angles of each associated corner column; and independent removable

angles only to the inner leg angles, whereby said intermediate leg angles may be separately removed.

5. In a structure of the nature disclosed, the combination of: relatively spaced triple-angle corner leg columns, each comprised of two opposed strings of inner leg angles and an intermediate string of outer leg angles arranged in intimate back-to-back contact to form a compact corner leg column substantially cross-shape in cross section, the leg angles of each string being vertically aligned to abut one upon another, the inner leg angles of said two opposed strings being horizontally aligned so that the leg angles of both said opposed strings abut at coincident levels, and the intermediate leg angles being disposed to break-joint with the inner leg angles; transverse girts forming the respective sides of the structure and connecting the adjacent corner leg columns; means for securing the girts of each side to the adjacent inner leg angles of each associated corner column; means connecting the inner leg angles of each corner leg column independently of the intermediate leg angles thereof; and independent means for securing the intermediate leg angles only to the inner leg angles, whereby said intermediate leg angles may be separately removed.

6. In a structure of the nature disclosed, the combination of: relatively spaced corner leg columns each formed of two opposed strings of vertically aligned leg angles with the flanges of each string disposed at right angles to the adjacent flanges of the opposed string, and with the inner flange of each string disposed parallel to the adjacent side of the structure and the other flange thereof extended outwardly, the leg angles of both strings being horizontally aligned to bring their respective abutment joints at coincident levels; transverse girts forming the respective sides of the structure and connecting the adjacent leg columns; means for securing the girts of each side to the adjacent inner flanges of the associated leg columns; intermediate angle connecting elements associated with each corner leg column and disposed between and in intimate contact with the outer flanges of both strings of leg angles thereof in positions to span said respective abutment joints; and separate means for securing said connecting elements to said outer flanges of the leg angles of both opposed strings.

7. A compound gusset bracket for a fabricated steel structure, comprised of: two angularly disposed vertical gusset plate portions having their adjacent vertical edges joined together; and two horizontal gusset plate portions each connected to a horizontal edge of one of said vertical gusset plate portions, said horizontal gusset plate portions extending inwardly in overlapping relation-

ship to provide a two-ply horizontal gusset.

8. A compound gusset bracket for a fabricated steel structure, comprised of: a single sheet metal stamping having two angularly disposed vertical gusset plate portions having their adjacent vertical edges joined together; and two horizontal gusset plate portions each connected to a horizontal edge of one of said vertical gusset plate portions, said horizontal gusset plate portions extending inwardly in overlapping relationship to provide a two-ply horizontal gusset.

9. In a structure of the nature disclosed, the combination of: relatively spaced triple-angle corner leg columns, each comprised of only two opposed strings of vertically aligned leg angles and one intermediate string of vertically aligned leg angles arranged in intimate back-to-back contact to form a compact corner leg column substantially cross-shape in cross section, the leg angles of both opposed strings of all of said leg columns being respectively of corresponding lengths so as to break joint at coincident levels, and the intermediate leg angles of each corner column being disposed in break-joint relationship with those of the companion opposed strings; and transverse girts forming the respective sides of the structure and connecting the adjacent corner leg columns, the girts of each side being secured to the adjacent opposed strings of the associated corner leg columns independently of the intermediate leg angles thereof.

10. In a structure of the nature disclosed, the combination of: a triple-angle corner leg column formed of two opposed strings of vertically aligned inner leg angles with the angles of each string horizontally aligned with those of the other string and an intermediate string of vertically aligned outer leg angles disposed in break-joint relationship with said inner leg angles, the three strings of leg angles being arranged in intimate back-to-back contact to form a compact corner leg column substantially cross-shape in cross section; reinforcing brackets positioned at opposite ends of said inner leg angles and secured thereto to form direct connections between both strings of inner leg angles; transverse girts forming adjacent sides of the structure, the girts of each side being secured to the adjacent inner leg angles and to said brackets; and means for

securing the intermediate leg angles only to the inner leg angles, whereby said intermediate leg angles may be separately removed.

11. In a structure of the nature disclosed, the combination of: a triple-angle corner leg column formed of two inner strings of vertically aligned leg angles with the angles of each string horizontally aligned with those of the other string, and an intermediate string of vertically aligned leg angles disposed in break-joint relationship with the inner leg angles, the three strings of leg angles being arranged in back-to-back relationship to form a corner leg column substantially cross-shape in cross section; compound gusset brackets reversely arranged in pairs and positioned at the abutting ends of the inner leg angles, each bracket having two vertical gusset plate portions joined together and two overlapping horizontal gusset plate portions each extending inwardly from one of said vertical gusset plate portions, each vertical gusset plate being secured to the adjacent inner leg angle and the horizontal gusset plates forming a direct connection between the two inner strings of leg angles; means securing the horizontal gusset plates of each pair of brackets together to connect the several leg angles of both inner strings; transverse girts and braces forming adjacent sides of the structure, the girts and braces of each side being secured to the adjacent inner leg angles and the adjacent brackets; and separate means for securing the intermediate leg angles to the inner leg angles independently of the girts, braces and brackets.

12. A combination as defined in claim 11 in which each girt is of angle form and is nested in a horizontal corner of one of said gusset brackets with its horizontal flange connected to the horizontal gusset plates of said bracket and its vertical flange connected to the adjacent vertical gusset plate of said bracket.

13. A combination as defined in claim 4 in which the girts of each side comprise upper girts secured to the upper ends of the inner leg angles of the associated corner leg columns and lower girts secured to the lower ends of said inner leg angles.

In testimony whereof, I have hereunto set my hand at Los Angeles, California, this 8th day of July, 1926.

CLARENCE B. FOSTER.
